UNITED STATES PATENT OFFICE.

IRVING J. BALL, OF BROCK, NEBRASKA.

HUSKING-MACHINE.

No. 834,247.

Specification of Letters Patent.

Patented Oct. 30, 1906.

Original application filed October 15, 1904, Serial No. 228,540. Divided and this application filed May 31, 1905. Renewed September 24, 1906. Serial No. 335,962.

To all whom it may concern:

Be it known that I, IRVING J. BALL, a citizen of the United States, residing at Brock, in the county of Nemaha and State of Nebraska, have invented certain new and useful Improvements in Husking-Machines, of which the following is a specification, reference being had therein to the accompanying drawings.

5 10 This case is a division of my patent or pending application, Serial No. 228,540.

The object of the present invention is the provision of a husking-machine wherein the peculiar manipulation of the ears in the different steps of the operation of the machine resembles, as near as possible, the more usual hand method of husking, so that the complete or clean husking of the ears is practically assured.

15 20 A convenient embodiment of the invention comprises means for causing the stalk to approach or rest upon the ground, means for separating the ears from the stalks, means for endwise reversing the ears to cause them to travel in the proper direction relative to the husking instrumentalities, means for removing the husks from one side of the ears, means for presenting the opposite side of the ears to other husking instrumentalities 25 30 in combination with the latter. This embodiment of the invention is illustrated in the accompanying drawings, and upon an inspection of the same in connection with the following detailed description the novel characteristics of the machine will be apparent.

35 In the drawings, Figure 1 is a vertical sectional view of the machine. Fig. 2 is a bottom view. Fig. 3 is a rear elevation. Fig. 4 is a detail perspective view of the means for separating the ears from the stalks, and Fig. 40 45 50 55 60 65 70 75 80 85 90 95 100 105 110 115 120 125 130 135 140 145 150 155 160 165 170 175 the finger, serving to fasten the lower ends of said blades in their respective recesses or seats.

Near the upper ends of the blades Q and 5 arranged transversely thereto I secure a cutter-bar R rigidly with the forward face of the beam P, the effective or operating portions of the cutter-bar being intermediate the guide-fingers and across the space therebetween.

As the stalks pass through the ways K their attached or lower ends first enter the spaces between the guide-fingers, and as the machine moves forward are drawn there-through, whereby the ears are caught between the fingers and guided by the diverging walls thereof to the cutter-bar R, which cuts the same from its butt and stalk, when the detached ear is in position for the succeeding manipulation, as will presently appear.

The purpose of the knife-blades Q is principally to cut up and lessen the hindrance offered to the progressive movement of the machine by foreign matter or stalks disposed across the path of movement of said blades and transversely of the line of travel of the machine; also, to keep the ears straight as they are cut from the stalks.

30 It is to be noted that as the machine travels in a forward direction and the ears are engaged by the guide-fingers O the separation of said ears from their stalks is strongly resisted by reason of the stalks holding fast to 35 the ground, so that when the ears are cut from the stalks by the cutter-bar R they project forwardly at substantially right angles to the cutter-bar in position to have their pointed ends caught by some of the teeth n, 40 disposed around the periphery of the rotary carrier N. This effects a reversal of the separated ears endwise, whereby they are carried through the machine point first.

The first husking operation may now be 45 described. The ears being carried in an upward direction by the carrier N toward the toothed roller S, the same are engaged by said toothed roller S, rotating in the direction of the arrow, whereby the ears are elevated 50 or pushed upwardly into the space between rotary husking devices T and the carrier N. This pushing-roll has several flanges s in line with the flanges M on the carrier N, whereby the proper alinement of the ears is maintained. One rotary husking device T is disposed directly opposite to each space between the peripheral flanges of the rotary carrier and they are independently supported and also independently actuated. The 55 peculiar character of the teeth t of the husker is perhaps best shown as being formed upon an arc conforming as near as possible to the average curvature of one side or half of an ear, whereby the husks on the side or half of 60 the ear presented to the teeth of the husking

device will be firmly grasped thereby and torn from the ear as the carrier rotates away from the same, the husking devices of course rotating in an opposite direction.

The husking devices T are, as previously 70 stated, yieldably supported, whereby they may automatically approach closer to or re-cede from the rotary carrier to accommodate ears of different thickness, the initial adjustment of the parts being of course for the 75 smaller-sized ears. The yieldable bearings comprise a main supporting-plate U, secured to the frame A of the machine and carrying a series of rearwardly-disposed tubular sleeves or guide-arms u, one for each husking device, 80 within which slidable bearing-boxes u' for said husking devices work back and forth. These boxes are guided in their movement by lugs u'', fitting the slots u² in the sleeve. The movement of the bearing-boxes in a rearward direction is resisted by springs u³, bearing at one end against the boxes and at their opposite end against an adjustable plug or screw u⁴, threaded into the open end of the sleeves, and through the medium of which 85 the tension of the springs is regulated. u⁵ are stems on the bearing-boxes guided by longitudinally-disposed apertures u⁶ in the plugs u⁴. u⁷ are hard-rubber bumpers.

The husking devices are driven by means 95 of sprocket-chains V, operated from gears v on a common drive-shaft v' and engaging the centrally-disposed gears v'' of the husking devices. As shown, the huskers are corrugated longitudinally. Its bearing-boxes are 100 preferably steel brass-lined.

It may happen that some of the ears separated from the stalks are too short to be engaged by the teeth n of the rotary carrier N, and in this event such short ears are simply 105 pushed upwardly by the succeeding ears and forwardly by inclined guides W, arranged immediately above the cutter-bar until the same are caught by the teeth n or the teeth of the pusher-roller S. Teeth w at the upper 110 edges of the guides W serve to prevent the short ears escaping rearwardly thereover and also constitute cleaners for the pusher-roller.

The ears having now been stripped of the 115 husks on one side thereof are carried upwardly and around the top of the machine by the rotary carrier N until they approach the husking instrumentalities for the opposite side of the ears mounted at the forward end of the main portion of the machine and which 120 will now be described, said ears having in the meantime been held in place upon the teeth of the carrier by freely-mounted gravity pressure-rolls X, the shafts x of which work in slots x' in arched side members x'' of the 125 frame of the machine.

Y designates a husking device mounted 130 relatively close to the rotary carrier N and fixed against bodily movement relative thereto to prevent the ears on the carrier passing

therebetween. This husking device extends entirely across the machine and is provided with properly-separated husking-teeth *y* of the same general character as the teeth *t* of the devices *T*, hereinbefore described. The husking device *Y* rotates in the direction of the arrow in opposition to a rotary feeding and pressing device *Z*, rotating in a contrary direction, one arranged opposite each peripheral set of teeth on the rotary carrier. The yieldable bearings for the feeding and pressing devices are represented at *z* and the common supporting-plate therefor at *z'*, it being unnecessary to go further into the detail of these as they are the same in structure as the corresponding elements hereinbefore defined in connection with the husking devices *T*. As the carrier approaches that part of the machine last referred to the centrifugal force incident to the rapid movement of the carrier will cause a separation of the ears therefrom, and said ears coming in contact with the foremost roller *X* will be guided thereby to the feeding and pressing devices *Z*, the headed pins *z''* of which will grab the ears and force them between the same and the husking device *Y*, the result being that the under or unhusked half or side of the ears will be presented to the teeth of the husking device *Y* and stripped from the ears thereby. The removed husks are carried around by the device *Y* and falling upon the inclined teeth and plate designated, respectively, at 2 and 3 are delivered to a chute 4, inclining outwardly and downwardly toward both sides of the machine, whereby the husks are conducted to the ground. The chute is mounted upon the stalk-bender *E*, so that the vibration of the latter incident to its engagement with the ground will shake the husks and cause a proper feed thereof through said chute to either the one or the other side of the machine. The cleaned or husked ears fall from between the husking device *Y* and the feeding devices *Z* into a hopper 5 therebeneath arranged at the rear end of a forwardly-extending upwardly-inclined endless elevator 6, adapted to carry the corn to the desired point of deposit.

50 Any convenient means may be employed to effect the desired rotation of the carrier *N*, a chain 9, engaging a sprocket 10 on the shaft of the carrier, being shown for that purpose. The chain 9 of course communicates with some suitable source of power, preferably the traction-wheels. A similar chain 14, engaging a sprocket 15 and a sprocket 16, imparts the proper movement to the drive-shaft *v'* for the husking devices *T*.

60 At the opposite end of the shaft *s'* I provide another sprocket 17, operating through the medium of a chain 18, rigid with shaft 11 and adjoining sprocket 14 and sprocket 19, to rotate the husking device *Y*, said husking

device in turn effecting the operation of the feeding and pressing devices *Z* by means of chain 20, running from the husking device to a drive-shaft 21, mounted at the forward upper end of the frame *A*, and a chain 22, running from said shaft to the shaft of each of the feeding and pressing devices *Z*, suitable sprockets being provided for this purpose.

Any convenient means may be utilized in operating the endless elevator 6.

The rotary carrier hereinbefore referred to is shown as hexagonal, the flat surfaces of which permit the corn carried thereby to lie flat thereon; but it is obvious that any shaped carrier found practical—for instance, one having a greater or less number of sides—may be substituted for that shown.

The forward pitch or inclination of the frame of the machine enables the proper mounting and disposition of the parts, while greatly decreasing the size and number of the parts of the same which would otherwise be required. It also enables the corn to be continually carried forwardly after leaving the initial husking devices and to shoot forwardly and downwardly by centrifugal force and gravitation to the second or final husking device, as before described.

Another feature of importance not heretofore observed is the disposition of the teeth *n* on the periphery of the rotary carrier *N*. It will be seen that these teeth are arranged in pairs, the teeth of each pair being so separated that they will not engage the center or thickest portion of the ears, but rather at points a little to the sides of the longitudinal center, which will give a firm hold on the husks and enable their ready removal without otherwise damaging the corn.

It is to be understood that the invention is susceptible of other embodiments than that disclosed herein.

Having thus described the invention, what is claimed as new, and desired to be secured by Letters Patent, is—

1. In combination with husking instrumentalities, means for feeding ears thereto including a carrier and a coöperating pusher arranged below the husking instrumentalities, and a cleaner for said pusher.

2. In combination with husking instrumentalities, means for feeding ears thereto, including a carrier and coöperating pusher-roll arranged below the husking instrumentalities, and a cleaner for said pusher-roll.

3. A husking-machine provided with means for husking one side of an ear and other means for subsequently husking the opposite side thereof, in combination with means for presenting the ears endwise to the husking means.

4. In a machine of the character described, a rotary carrier, husking means operatively associated therewith, and other husking

- means also operatively associated therewith, said means operating in sequence to remove different portions of the husks of an ear, in combination with means for presenting the 5 ears endwise to the husking means.
5. In combination with a series of husking devices, a single carrier for endwise presenting different portions of the ears thereto.
6. In combination with a series of husking 10 devices, a single rotary carrier for the ears arranged to endwise present the outer side of the ears to one of the husking devices and the other side thereof to the other husking device.
- 15 7. In a machine of the character described, means for husking one side of the ears, other means for subsequently husking the opposite side thereof, and means whereby the cleaned ears and husks are separated and 20 conducted away from the machine in combination with means for presenting the ears endwise to the husking means.
8. In combination with a rotary carrier, husking instrumentalities, and means for 25 pushing the ears upwardly toward the husking instrumentalities, said husking instrumentalities being arranged above said pushing means.
9. In combination with a rotary carrier, 30 husking instrumentalities, and a pusher-roll for forcing the ears upwardly toward the husking instrumentalities, said husking instrumentalities being arranged above said pusher-roll.
- 35 10. In a machine of the character described, a rotary carrier, means for presenting the ears point first to the carrier, in combination with separated husking instrumentalities operating in sequence to remove the 40 husks from the opposite side of the ears.
11. In a machine of the character described, a rotary carrier, means for presenting the ears point first to the carrier, in combination with separated husking instrumentalities for successively removing the husks 45 from the opposite sides of the ears, and means for pushing the ears upwardly toward the initial husking devices.
12. In a machine of the character described, 50 a carrier, husking instrumentalities, and means therebeneath in addition to the carrier for elevating the ears into operative relation thereto.
13. In a machine of the character described, 55 a carrier, husking instrumentalities, and a rotary pusher therebeneath in addition to the carrier for forcing the ears into operative relation therewith.
14. In a machine of the character described, 60 a rotary carrier, husking instrumentalities in rear thereof, other husking instrumentalities in front of the carrier, and a supporting-framework for the several parts having a pitch or inclination in a forward direction.
15. In a machine of the character described, a carrier, a husking device operating in conjunction with the carrier to remove the husks, and a yieldable bearing for said husking device acting to force the same toward 70 the carrier.
16. In a machine of the character described, a carrier, a husking device operating in conjunction with the carrier to remove the husks, and a yieldable bearing for said 75 husking device acting to force the same toward the carrier comprising a bearing-box, a sleeve within which the box slides, an adjustable plug at the outer end of the sleeve, and a spring interposed between said adjustable 80 plug and the bearing-box and confined within the sleeve.
17. In a machine of the character described, a carrier, a husking device operating in conjunction with the carrier to remove 85 the husks, and a yieldable bearing for said husking device acting to force the same toward the carrier comprising a bearing-box, a sleeve within which the box slides, an abutment at the outer end of the sleeve, and a 90 spring interposed between said abutment and the bearing-box and confined within the sleeve.
18. In a machine of the character described, a rotary husking device having husking-teeth arranged in series in an arc to conform 95 to the general outline of an ear, means for rotating the same, and a coöperating rotary carrier the axis of which is approximately parallel to that of the husking device.
19. In a machine of the character described, a rotary husking device comprising a rotatable member having a series of husking-teeth arranged in an arc to conform to 105 the general outline of an ear, and means for rotating the same.
20. In combination with a husking device, means for rotating the same, and a yieldably-supported rotatable feeding and pressing device provided with headed pins coöperating 110 with said husking device.
21. In a machine of the character described, a rotary carrier, a husking device operatively associated therewith, means for rotating said husking device, and a yieldably-mounted feeding and pressing device provided with headed pins arranged to engage the ears discharged from the rotary carrier 115 and to force the same into operative relation to the husking device.
22. In a machine of the character described, a rotary carrier, a husking device operatively associated therewith, means for rotating said husking device, and a yieldably-mounted feeding and pressing device arranged to engage the ears discharged from the rotary carrier and to force the same into operative relation with the husking device.
23. In combination with husking instru- 130

5 mentalities, means for feeding ears thereto, including a rotary carrier and a coöperating pusher-roll, a cleaner for said pusher-roll, and means operatively associated with said carrier and pusher-roll for initially separating the ears from their stalks.

24. In combination with husking instrumentalities, means for feeding ears thereto, including a rotary carrier and a coöperating 10 pusher, a cleaner for said pusher, and means operatively associated with said carrier and pusher for initially separating the ears from their stalks.

25. In combination with husking instrumentalities, means for feeding ears thereto including a carrier and coöperating pusher-roll, a cleaner for said pusher-roll, and means operatively associated with said pusher-roll and carrier for initially separating the ears 20 from their stalks.

26. In a machine of the character described, means for separating the ears from a stalk and for presenting them end first to the husking means, means for husking one 25 side of the ears, and other means for subsequently husking the opposite side thereof.

27. In a machine of the character described, means for engaging a stalk, means for separating the ears from the stalk and for 30 presenting them end first to the husking means, means for husking one side of the ears, other means for subsequently husking the opposite side thereof, and means whereby the cleaned corn and husks are separated.

35. 28. In a machine of the character described, means for bending a stalk toward the corn - husking means, and instrumentalities for separating the ears from the stalk and reversing them endwise prior to any husking 40 operation for presentation to the husking means.

29. In combination with husking instrumentalities, means for separating the ears from a stalk and for reversing said ears endwise 45 for presentation to said husking instrumentalities, and a carrier for presenting the ears point first to the husking instrumentalities.

30. In a machine of the character described, a carrier for presenting the ears 50 point first to the husking instrumentalities, means for engaging the stalks, means for separating the ears from the stalks and for reversing said ears, and means operatively associated with the carrier for husking the ears.

55. 31. In a machine of the character described, a carrier for presenting the ears point first to the husking instrumentalities, means for engaging the stalks, means for separating the ears from said stalks, means for 60 husking one side of the ears, and other means for subsequently husking the opposite side thereof.

32. In a machine of the character described, a carrier for presenting the ears 65 point first to the husking instrumentalities,

means for engaging the stalks, means for separating the ears from the stalks and whereby the ears are reversed, means for husking one side of the ears, and other means for husking the opposite side thereof.

70

33. In a machine of the character described, a rotary carrier, means for separating the ears from the stalk, and for presenting the separated ears to the carrier, husking instrumentalities in rear of the carrier, other 75 husking devices in front of the carrier, and a supporting-framework for the several parts having a pitch or inclination in a forward direction.

34. In a machine of the character described, a stalk-bender, means for separating the ears from the stalk, means for husking said ears and for separating the cleaned ears from their husks, and a trough mounted on the stalk-bender and vibrated thereby arranged to receive the husks and conduct them away from the machine.

35. In a machine of the character described, husking means for operating on one side of the ears, other husking means for operating on the opposite side of the ears, and a carrier provided with means for engaging and positively holding the ears from turning when presented to the first husking means.

36. In a machine of the character described, husking means for operating on one side of the ears, other husking means for operating on the opposite side of the ears, and a carrier provided with means for engaging and positively holding the ears from turning when 100 presented to the first husking means, said holding means being arranged to present the ears end first to the husking means.

37. In a machine of the character described, husking means for operating on one 105 side of the ears, other husking means for operating on the opposite side of the ears, and a carrier provided with means for engaging and positively holding the ears from turning when presented to the first husking means, and auxiliary means for maintaining the ears in their initial position during the travel of the carrier from one husking means to the other.

38. In a machine of the character described, husking means for operating on one 115 side of the ears, other husking means for operating on the opposite side of the ears, and a carrier provided with means for engaging and positively holding the ears from turning when presented to the first husking means, said holding means being arranged to present the ears end first to the husking means, and auxiliary means for maintaining the ears in their initial position during the travel of the carrier from one husking means to the other.

39. In a machine of the character described, husking means for operating on one side of the ears, other husking means for operating on the opposite side of the ears, and a carrier provided with means for engaging and 130

positively holding the ears from turning when presented to the first husking means, and auxiliary means for maintaining the ears in their initial position during the travel of the carrier from one husking means to the other, including rotatable pressure devices above the carrier and between which and the carrier the ears pass.

40. In a machine of the character described, husking means for operating on one side of the ears, other husking means for operating on the opposite side of the ears, and a carrier provided with means for engaging and positively holding the ears from turning when presented to the first husking means, said holding means being arranged to present the ears end first to the husking means, and auxiliary means for maintaining the ears in their initial position during the travel of the carrier from one husking means to the other, including rotatable pressure devices above the

carrier and between which and the carrier the ears pass.

41. In a machine of the character described, husking means for operating on one side of the ears, other husking means for operating on the opposite side of the ears, and a carrier provided with means for engaging and positively holding the ears from turning when presented to the first husking means, and auxiliary means for maintaining the ears in their initial position during the travel of the carrier from one husking means to the other, including gravity pressure devices above the carrier and between which and the carrier the ears pass.

In testimony whereof I affix my signature in presence of two witnesses.

IRVING J. BALL.

Witnesses:

W. E. TRAVIS,
S. VANDEVORT.
